(57) **CLAIM**

The ornamental design for a wallet as shown and described.

DESCRIPTION

FIG. 1 is a front, first side, and top perspective view of a wallet embodying the new design;

FIG. 2 is a back, second side, and bottom perspective view thereof;

FIG. 3 is a front view thereof;

FIG. 4 is a back view thereof;

FIG. 5 is a top view thereof;

FIG. 6 is a bottom view thereof;

FIG. 7 is a first side view thereof; and,

FIG. 8 is a second side view thereof.

The uniform repeating broken lines shown in the figures depict portions of the wallet that form no part of the claimed design.

1 Claim, 8 Drawing Sheets
